UNITED STATES PATENT OFFICE

91,818

DESIGN FOR A BEAUTY BOX

Lurelle Guild, Darien, Conn., assignor to C. F. Church Mfg. Co., Holyoke, Mass., a corporation of Massachusetts

Application August 26, 1933, Serial No. 49,135

Term of patent 7 years

all whom it may concern:

Be it known that I, LURELLE GUILD, a citizen of the United States, residing at Darien, in the county of Fairfield and State of Connecticut, have invented a new, original and ornamental Design for a Beauty Box, of which the following is a specification, reference being had to the accompanying drawing, forming part thereof.

Fig. 1 is a perspective view of a beauty box showing my new design as it appears with the combined cover and mirror of the box in the open position; and

Fig. 2 is a perspective view similar to Fig. 1 of the same box showing my new design as it appears with the cover in the closed position.

I claim:

The ornamental design for a beauty box substantially as shown and described.

LURELLE GUILD.
